(57) **CLAIM**

The ornamental design for an infrared thermograph, as shown and described.

DESCRIPTION

FIG. 1 is a front elevational view of the infrared thermograph;

FIG. 2 is a rear elevational view thereof;

FIG. 3 is a right-side elevational view thereof;

FIG. 4 is a left-side elevational view thereof;

FIG. 5 is a top plan view thereof;

FIG. 6 is a bottom plan view thereof;

FIG. 7 is a perspective view thereof with the camera portion in an inclined orientation; and,

FIG. 8 is an exploded view thereof.

In the drawings, the broken lines are for the purpose of illustrating portions of the infrared thermograph that forms no part of the claimed design.

1 Claim, 6 Drawing Sheets(56)
